REED FOR CLARINETS AND SAXOPHONES

Filed Nov. 5, 1927

Charles O. Widmayer

Inventor

UNITED STATES PATENT OFFICE

CHARLES O. WIDMAYER, OF CLEVELAND, OHIO

REED FOR CLARINETS AND SAXOPHONES

Application filed November 5, 1927. Serial No. 231,256.

My invention relates to improvements in the construction of reeds for reed musical instruments and more particularly for instruments such as clarinets and saxophones and 5 other reed instruments.

The object of my invention is to provide reeds with more uniform qualities for vibration and effective operation as compared to reeds constructed solely of reed cane.

10 Reed cane in itself consists of grain and fibre largely of irregular and crooked growth and when, in this state, it is constructed into reeds of their full length and size, the irregularity of its growth does not admit of easy 15 and free vibration and of good tone production. To supply the more uniform qualities above referred to I use reed cane in shorter lengths which does away in part with long continuous grain and fibre of irregular 20 growth, and combine these shorter lengths with like or other resilient materials in sections, thus constructing the reed as a whole. Also when it is desired to construct the reed in one continuous length of reed cane the 25 same improved results of more efficient operation are obtained by removing portions of the reed cane about the fulcrum point of the reed by cutting slots through the cane or by otherwise removing portions of it and the removed portions are replaced with more resilient 30 materials. In these methods of construction waste, from non-operating reeds, is largely eliminated to the benefit of the consumer.

35 My invention will be more readily understood by reference to the accompanying drawings forming a part of this specification in which Figure 1 is a plan view of the lay side of the reed in one form.

40 Figure 2 is a longitudinal section taken on line 2-2 of Figure 1.

Figure 3 is a vertical cross section on line 3-3 of Figure 1.

45 Figure 4 is another form of my invention, showing a side elevation of a mouthpiece with a reed having an interchangeable vibrating section, applied thereto and shown in section.

Figure 5 is a plan view of the lay side at the intersection.

50 Figure 6 is a vertical cross section of the

reed intersection taken about on the line 6-6 of Figure 4.

Figure 7 is another form of my invention showing a longitudinal section of a reed slotted through the body about the fulcrum point 55 to receive a material having more resiliency than that of reed cane and shown here with spring wires being imbedded in cement.

Figure 8 is a vertical cross section taken on line 8-8 of Figure 7.

Figure 9 is a modified form of Figure 7 showing a vertical cross section of a reed slotted only part way through the cane and reinforced with more resilient materials similarly as in Figure 7.

Figure 10 is another form of my invention showing a plan view of the reed from the outside, having a resilient spring plate attached at the fulcrum point on the lay side, with the reed having a recessed portion on the 70 opposite side varying in size to meet the desired requirements of strength.

Figure 11 is a side elevation of Figure 10.

Figure 12 is a vertical cross section on line 12-12 of Figure 10.

Figure 13 is a modified form of Figure 11, showing an interchangeable vibrating section.

Figure 14 is another form of my invention showing a longitudinal section of the reed on 80 line 14-14 of Figure 15; the reed being shown mounted on a partial view of the mouthpiece, containing the lay, and the vibrating section of the reed having attached to it a resilient spring plate forming an 85 interchangeable vibrating section with a clamped section which is secured to the mouth piece by screws.

Figure 15 is a plan view of the lay-side of the reed of Figure 14.

Referring to Figure 1, 1 is the vibrating section of the reed, joined to a resilient clamped section 2 by the interlocking prongs 3 and secured by cement 4. A ligature 8 shown in Figure 4 clamps the reed portion 2, 95 which constitutes the clamped section of the reed, to the lay of the mouthpiece 10.

For interchangeability the section 1^a is secured only by the prongs 3^a and the clamping plate 11 and the resilient spring plate 12 100

which form sockets 13 where plates 11 and 12 are secured together by means 14, enclosing the sides of the pronged plate 15, a depression 16 in the reed 1^a receives the small projecting hook 17 in spring like fashion, preventing the release of the section 1^a when in use.

In Figures 7, 8, and 9 a continuous member 1^b constitutes the reed to which is supplied 10 resilient members 20 in the form of straight wire springs imbedded in cement; these springs 20 are shown in slotted portions 24, in Figures 8 and 9, whereby the reeds 1^b and 1^c respectively, are reinforced with resilient 15 spring wire members imbedded in cement.

In Figure 10 the resilient member 25 is shown having clinching prongs 26 added at the fulcrum point 27 shown in Figures 10 and 11 and clinched to the reed about the fulcrum 20 point giving resiliency to the vibrating end of the reed 1^c (Figure 11) and the reed is shown recessed at 29 (Figure 12) to suit individual requirements.

An interchangeable vibrating end 1^c (Figure 13) is constructed separately from the clamped end 2^c and joined at 30 and retained by friction 31 and clinched at 32 by the resilient plate 25^c which extends along the lay side of the reed from the fulcrum point backwardly on the clamped end 2^c.

In Figures 14 and 15 is shown a combined resilient plate 25^f with vibrating end 1^f attached to the clamped end 2^f by means 35; the clamped end 2^f is secured to the mouthpiece by means 36, forming a support for the vibrating end 1^f combined with resilient plate 25^f.

The operation of my reed as a whole is in like manner to that of other reeds, however, 40 by the methods of construction, herein disclosed, the vibration is increased, and operation facilitated by combining other more resilient materials with the reed cane.

Although the foregoing is necessarily of a 45 detailed character, in order that the invention may be completely set forth, it is understood that the specific terminology is not intended to be restrictive or confining, and that the various re-arrangements of parts 50 and modifications of structural detail may be resorted to without departing from the scope or the spirit of the invention as herein claimed.

What I claim is:

- 55 1. A reed for wind musical instruments consisting of sections, joined and cemented together.
2. A reed for wind musical instruments consisting of sections, said sections being detachable.
- 60 3. A reed for wind musical instruments consisting of sections of reed cane securely joined and cemented together.
4. A reed for wind musical instruments 65 consisting of a part of reed cane and a part

of other resilient material joined to said reed cane.

5. A reed for wind musical instruments comprising a vibratory section and a clamped section, securely joined together.

6. A reed for wind musical instruments comprising a vibrating section and a clamped section of a more resilient material joined at the fulcrum point.

7. A reed for wind musical instruments comprising a vibrating section, and a clamped section having a more resilient material; the vibrating section being removable.

8. A reed for wind musical instruments, comprising a vibrating section, and a clamped section; the vibrating section being joined to and removable from the clamped section.

9. A reed for wind musical instruments, comprising a vibratory section and a clamped section; the vibratory section joined to and removable from the clamped section; the clamped section comprised of a resilient plate at the lay side of the reed, a clamping plate at the upper side of the reed, and with intermediate pronged members forming sockets to receive the vibratory section which also has pronged members of equal proportions to those of the clamped section for interlocking with said clamped section.

10. A reed for wind musical instruments 95 comprising a removable vibratory section, and a clamped section, the clamped section having affixed a resilient plate extending along the lay-side of the clamped section and attached thereto; the vibratory section being joined about the fulcrum point, with the resilient plate attached to the clamped section.

11. A reed for wind musical instruments comprised of a continuous member with a resilient plate applied on the lay-side at about 105 the fulcrum point and secured thereto.

12. A reed for wind musical instruments comprised of a continuous member slotted through the body longitudinally at about the fulcrum point and the slotted portion replaced and reinforced by more resilient material.

13. A reed for wind musical instruments comprised of a continuous member having a longitudinally slotted portion at its fulcrum point, cement, and wire spring means imbedded therein and located in the slotted portion.

14. A reed of the class described, comprising, in combination, a section adapted to be fastened to the mouthpiece of a wind musical instrument, and a vibrating section of reed connected to said first named section.

15. A reed of the class described, comprising, in combination, a section of resilient material adapted to be fastened to the mouthpiece of a wind musical instrument, and a vibrating reed section of comparatively short length as compared to the whole, connected to said first named section to provide a com- 125 130

posite reed wherein the grains of the reed are substantially straight in character.

16. In a wind musical instrument, the combination with a mouthpiece, of a reed for the said instrument, said reed comprising a section positively secured to the mouthpiece, and a vibrating section of reed detachably connected to said first named section.

In testimony whereof I hereunto affix my signature this 3d day of November, 1927.

10 CHARLES O. WIDMAYER.
